UNITED STATES PATENT OFFICE.

JOHN J. CRALL, OF KENDRICK, OKLAHOMA.

MACHINE FOR FORMING CONCRETE DIKES.

1,164,072.

Specification of Letters Patent. Patented Dec. 14, 1915.

Application filed January 7, 1913. Serial No. 740,642.

To all whom it may concern:

Be it known that I, JOHN J. CRALL, citizen of the United States, residing at Kendrick, in the county of Lincoln and State of 5 Oklahoma, have invented certain new and useful Improvements in Machines for Forming Concrete Dikes, of which the following is a specification.

My invention relates, generally speaking, 10 to excavating and filling in machinery, and particularly to machines designed to be used on levees or like structures for the purpose of forming a concrete dike or core for the levee.

15 The general object of my invention is the provision of a machine adapted to cut a trench longitudinally along the crown of a levee, dam or like structure and fill in the trench or cut with artificial stone or concrete so as to form a wall, dike or core extending longitudinally along the levee and of any desired depth therein.

Another object is the provision in one 25 single machine of means for cutting the trench, mixing concrete, conducting the plastic mass into the trench and for supporting the earth on each side of the trench.

Other objects will appear in the course of the following description.

30 My invention is illustrated in the accompanying drawings wherein:—

Figure 1 is a side elevation of a machine constructed in accordance with my invention. Fig. 2 is a plan view of the machine 35 illustrated in Fig. 1. Fig. 3 is a sectional elevation taken on the line 3—3 of Fig. 2 but being enlarged in scale. Fig. 4 is a section on the line 4—4 of Fig. 2. Fig. 5 is a section on the line 5—5 of Fig. 2. Fig. 6 40 is an enlarged fragmentary side elevation of part of the frame of the machine, the excavating mechanism, the trench sheaths and the chutes whereby the plastic concrete is carried into the space between said sheaths.

45 Fig. 7 is a fragmentary section of the lower end of the excavating carrier support and the sprocket wheel therefor and showing the bearing for the sprocket wheel. Fig. 8 is 50 an enlarged horizontal section of a portion of the sheathing section. Fig. 9 is a perspective view of the chute 145.

Corresponding and like parts are referred

to in the following description and indicated in all the views of the accompanying drawings by the same reference characters.

55

The frame of the machine comprises parallel, longitudinal beams 2 connected at their ends by transverse beams 3. Intermediate longitudinal beams 4 and 5 are supported at their ends by the beams 3, the 60 beams 5 being preferably faced with metal strips 5^a so as to form a track. Rising from opposite end portions of the beams 2 are pairs of standards 6 and 7 which are connected at their upper ends by cross beams 8. 65 Beneath these cross beams and connected thereto in any suitable manner are a pair of longitudinal supporting beams 9. The frame of the machine is mounted upon wheels in any desired way. Running boards 70 10 are supported near the upper ends of the standards 6 and 7. Side platforms 11, designed to receive the engines for operating the machine, are mounted upon the frame of the machine.

75

Mounted upon the rear end of the machine is a concrete mixer, preferably consisting of a drum 12, rotatably mounted upon rollers 13 and formed with a centrally disposed gear wheel 14. The drum is open 80 at opposite ends, and located at the rear end thereof is a hopper 15 while at the forward end of the drum is disposed a cut-off spout. A shaft 16 passes through the length of the drum and is connected thereto by radiating 85 arms 17. This shaft, at its rear end, is provided with blades 18 set helically to act as an interrupted screw conveyer which projects into a lateral extension 19 of the hopper which projects into the opening of the 90 drum. The inner face of the drum is provided with longitudinally extending ribs, ledges or flanges 20 which act to mix the material as the drum is rotated. The forward end of the drum is provided with a centrally 95 disposed sleeve 21 through the center of which the shaft 16 passes. The shaft 16 at its forward end is provided with a plurality of blades 18^a arranged helically to form a screw conveyer which extends from a point 100 inside the drum to a point exterior thereto. Surrounding the screw conveyer 18^a is a spout 22 rotatably mounted in suitable supporting bearings 23 and provided with a

handle 24^a whereby it may be rotated. This spout is cylindrical in form but the rear portion thereof, slightly in front of the rear end of the sleeve 21, is cut away, as at 24, so that the spout at its rear end is approximately trough-shaped in cross section. The front end of the spout is open but the rear end is closed by means of a disk 25 through which passes the shaft 16. When 10 the spout is turned to the position shown in Fig. 5, that is, with the handle 24^a upward, the material which is being continually carried upward and forward by the drum drops into the trough-shaped portion of the 15 spout and is moved therethrough by the screw 18^a. When, however, the spout is turned to bring the opening or cutaway portion 24 downward and the closed bottom portion upward no material can fall into 20 the spout; hence the discharge of the material through the spout is cut off.

The drum is driven by means of a shaft 26 supported in suitable bearings upon the side frame of the machine and driven from 25 an engine 27. This shaft has splined upon it a sprocket wheel 28. A counter-shaft 29 is mounted upon the supporting frame and carries upon it a sprocket wheel 30 from which passes a chain 31 over the sprocket 30 wheel 28. The shaft 29 carries a spur gear, or pinion 32, which engages with the gear 14. The drum 12 is rotatably mounted upon side beams 33 which also support the spout and hopper. The side beams 33 are connected so as to form a frame which is mounted upon the beams 5, as a track, so that the drum or concrete mixer may be shifted longitudinally along the machine.

Mounted near the forward end of the machine just rearward of the front wheels is an upwardly extending standard 34. The lower end of this standard is provided with a U-shaped clamping member 35 which embraces a shaft 36 mounted in pillow blocks 37 projecting upward from the frame of the machine. The standard 34 is formed with a plurality of transverse holes 39 disposed at intervals along its length for the purpose of holding the excavating mechanism in vertically adjusted positions.

Vertically slidably upon the standard 34 is a frame comprising spaced blocks 40 which embrace opposite sides of the standard. These blocks are connected at the top 55 by a covering plate 41, and bolted to the inside faces of the blocks are the rearwardly projecting brackets 42. Secured to the inside faces of the blocks 40 by transverse bolts 43 is a pair of downwardly extending plates 44 forming an elevator supporting frame. The plates are longitudinally slotted as at 45. Rotatably disposed in the lower end of the supporting frame is a sprocket wheel 46 and rotatably mounted in 60 the upper end of the frame is a sprocket

wheel 47 fastened to a shaft 48 which extends through the plates 44, on each side, and is supported in journal bearings 49 mounted upon pillow blocks 50 which are attached to the plates 44 and are also supported by means of bolts 51 depending from the blocks 40.

In order to raise or lower the elevator supporting frame, I provide a winding drum 52 mounted upon the beams 9. This drum is provided with a gear wheel 53 intermeshing with a pinion 54 mounted upon a crank shaft 55 designed to be turned by hand. This crank shaft is provided with a ratchet wheel 56 engaged by a pawl 57 so that the winding drum may be held at any desired point. When the elevator frame is raised to the proper height, it is held in adjusted position by transverse pins 58 passed through apertures in the forward ends of 80 the blocks 40 and the apertures 39 in the standard 34. Disposed at the lower end of the standard 34 and extending rearwardly therefrom are the arms or links 59, the outer ends of which are inwardly bent, 85 as at 60, to engage within the slots 45 and thus hold the plates 44 of the elevator frame in parallel relation to the standard 34. Opposite the engine 27 is an engine 61 of any suitable type which is operatively geared 90 with a longitudinal shaft 62 supported in suitable bearings upon the frame of the machine and which extends from front to rear thereof. A friction wheel 63 secured upon the shaft 62 engages a disk 65 mounted upon a shaft 66 which at its outer end is disposed in a journal bearing 67 and which at its inner end is rotatably received within a bore formed in the end of the shaft 36. A bevel gear wheel 68 is mounted upon the shaft 105 66 to rotate therewith and is free to move thereon and is in mesh with a miter gear 69 fastened to a vertical shaft 70 which is rotatably supported in a cross piece 71 attached to the standard 34. The shaft 70 is journaled at its upper end in a bearing 72 which is connected to and extends outward from one of the blocks 40. A shaft 48^a paralleling the shaft 48 is mounted in bearings 49^a provided upon the pillow blocks 50. The shaft 110 48^a is provided at one end with a bevel pinion 73 which meshes with a bevel pinion 74 splined upon the shaft 70. The bevel pinion 74 is held in engagement with the pinion 73 by means of a bracket 75 attached to an extension of the adjacent pillow block 50. The shaft 48^a at its opposite end carries a pinion 76 which meshes with a gear wheel 77 mounted upon the shaft 48. Thus motion is transmitted from the engine 61 to the 115 shaft 48 and thus to the excavating carrier.

For the purpose of laterally adjusting the standard 34 and the elevator carrier frame and the excavating carrier, I provide an ad- 120

justing screw shaft 80 mounted in a suitable bearing 81 and having screw threaded engagement with a screw threaded bore formed in the extremity of the trunnion 36 as at 82. The trunnion is laterally shiftable in its bearings 37, hence when the screw 80 is turned, the trunnion is shifted laterally in one direction or the other. To laterally shift the upper end of the standard 34, a screw shaft 83 is mounted in suitable bearings upon the beams 9 and has screw threaded engagement with ears 84 projecting from the standard 34. The outer end of this shaft 83 is provided with a sprocket wheel 85 over which passes a sprocket chain 86 which passes around a sprocket wheel 87 carried upon the shaft 80. A bevel gear 88 secured to the outer end of the shaft 80 meshes with a bevel gear 88^a mounted upon a forwardly and upwardly inclined shaft 89 carrying at its end a hand wheel 90. This hand wheel is disposed in such position that an operator standing upon the front of the machine may easily shift the excavating mechanism laterally so as to keep it in proper alignment.

The endless chain excavator and elevator passing over the sprocket wheels 46 and 47 is indicated at 94 and may be of any construction so long as it operates to remove the earth on the forward side and carry the loose earth upward and discharge it into a trough 109.

Depending from the rear ends of the pil- 30 low blocks 50 are hangers formed by bolts 107 and a transverse bar 108. Supported in these hangers is a transversely extending conveyer trough 109 within which the conveyer 110 is located (see Fig. 3) whereby 40 the earth dumped into the trough from the buckets 104 is conveyed laterally and discharged at the side of the machine. This conveyer 110 is supported upon pulleys within the trough 109 in any well known manner. One of the pulleys has its shaft ex- 45 tended, as indicated at 111; and a sprocket chain 106 connects the shaft 111 with a shaft 106^a by passing around sprocket wheels secured to such shafts. The shaft 106^a is 50 geared to the shaft 48, as shown most clearly in Fig. 1. The conveyer trough 109 is preferably made in a plurality of sections, two being illustrated, which are hinged in such a manner as to admit of the outer section being 55 turned upward into a vertical position or folded.

Fig. 7 illustrates the preferable way of mounting the wheels 46 and 47. In this figure 44 designates the side plates of the ele- 60 vator or carrier frame. Bolted or otherwise attached to the inside faces of these plates 44 are blocks 112. Each of these blocks is formed with a central circular recess to receive the adjacent terminal end of a sleeve 113. Passing through the sleeve 113 is a fixed

shaft 115 having internally screw threaded bores at its ends engaged by screws 116 which pass in from the exterior faces of the plates 44. Immediately surrounding and rotatable upon the sleeve 113 is a sleeve 117 70 which is secured to the sprocket wheel by means of a key 118 so as to rotate therewith. The object of this construction is to provide renewable bearing sleeves.

Disposed rearward of the excavating and elevating chain or carrier are a plurality of sheathing sections 119, 119^a and 119^b. There are as many of these sheathing sections as may be found desirable. These sheathing sections extend into the trench cut by the excavating carrier to shore up the sides of the trench until the concrete can fill the same. The sheathing member 119 consists of opposed plates 120, preferably of sheet metal, which are held spaced apart by means of strips 121 and 122. The strip 121 is disposed at the forward edges of the plates 120 parallel to the rear edges of the plates 44 and therefore parallel to the path of travel of the cutting knives and buckets of the carrier. 85 The strip 122, however, is disposed inward of the rear edges of the plates 120 and projects upward beyond these plates as at 120^a. This upward extension 120^a is connected by means of a U-bolt 124 to a pintle 125 which extends 90 through the blocks 42 and is provided at its upper end with a nut 126. The extension 120^a and the pintle 125 provide a pivotal support for the casing section 119 to turn. The casing section 119 is connected to the plates 100 44 by means of links 127 which are connected respectively to the section 119 and the plates 44 by means of a transverse bolt 128 and by a transversely extending trunnion member 129 which is disposed within slots 130 cut in 105 the forward edges of the plates 120 and in the forward face of the strip 121. This trunnion member 129 is pivoted to the strip 121 by means of a vertical pin 131. The lower end of the section 119 is forwardly curved 110 and elongated as at 132 to form a toe whose forward face conforms in curvature to the path of travel of the endless carrier. The sole 133 of the foot thus formed extends downward and rearward so that the heel of 115 this member 119 is lower than the toe 132. This acts to slightly compress and slide upon the material at the bottom of the trench and prevents the liquid cement from flowing forward of the sole 133 and getting into position to be taken up by the elevator.

The section 119^a and the section 119^b are constructed in a similar manner to the section 119, that is, each is composed of spaced plates 120^a and intermediate vertically ex- 125 tending front and rear strips. The front and rear strips of the section 119^a are indicated at 121^a and 122^a, respectively, and the corresponding strips of the section 119^b at 121^b and 122^b. The lower ends of the side plates 130

120^a are beveled downward and forward, as at 134, (Fig. 1). The strip 121^a is hinged at its upper end to the strip 122 by eye-members 135 and 136 and a pintle 137. The strip 5 121^a is hinged intermediate of its ends to the strip 122 by eye members 138 and 139 and a pintle 140. The section 119^b is hingedly connected to the section 119^a in substantially the same manner.

10 The side plates of the several sheathing sections are provided with a plurality of perforations 141 which extend in a line upward and rearward for the purpose of adjustably connecting a chute supporting member 142 to the sections. The member 142 is U-shaped and has opposed eyes 143 formed at its forward end through which passes a pin 144, which pin is adapted to pass through any one of the perforations 141. A chute 145 is 15 arranged between the lower ends of the side plates of the rear section and is adjustable vertically of the connection 142. This chute preferably consists of a single sheet of metal bent so as to form parallel sides 146 which 20 are spaced a sufficient distance apart so that they may be inserted between the side plates 120^a. A runner 148 is attached to the lower end of the chute and is strengthened by means of a brace 149 which is engaged at its 25 upper end by means of the link 142. A spout 150 leading from the mixing drum extends into the widened upper end of the chute 145. It may happen that the chute when raised by the runner 148 will stick and need to be 30 forced downward into normal position. I have therefore provided a manually actuatable rod 151 which extends upward to a position above the platform from which the mechanism is operated and which at its lower 35 end is pivotally connected to the rear upper corner of the chute 145 at 151^a.

40 Mounted upon the upper longitudinal beam 9 adjacent the rear standard 6 is a rope winding drum 152 having at one end a ratchet wheel 153 engageable by a pawl 154. The opposite end of the drum is provided with a pinion engaged by a gear wheel 155 mounted on a crank shaft 156. The purpose 45 of this winding drum or shaft will be later stated. Both of the winding drums 52 and 152 are disposed upon the longitudinal beam 9 in such position that an operator upon the running board 10 may readily operate them to handle either the excavator frame or the 50 several sheathing members.

55 While traveling upon an ordinary road, the machine may be driven by its own power in a manner which will be perfectly obvious to those skilled in the art. When at 60 work, the machine is intended to be drawn forward by means of a cable, chain or other flexible connection 157, attached at its forward end to any suitable anchorage, the inner end of such connection being wound 65 upon a winding shaft 158, mounted in suit-

able bearings between the beams 5. One end of the shaft is provided with a toothed gear wheel 159 and mounted above this gear wheel and extending transversely to one side of the machine is an actuating shaft 160 70 carrying upon it a pinion 161 which meshes with the gear wheel 159. This shaft 160 is also provided with a ratchet wheel 162 co-acting with a pawl 163. The outer end of the shaft 160 is provided with a friction 75 disk 164 adapted to be engaged by a driving friction disk 165 mounted upon the shaft 26. This friction disk 165 is adapted to be shifted across the face of the disk 164 so as to secure varying speeds of the shaft 160 80 in a manner well known in the art.

85 Preferably, I provide a form of variable friction drive so constructed that the friction wheel or wheels may be forced against the friction disk 164 with any desired pressure. To this end, I provide a counter-shaft 166 which extends parallel to the shaft 26 and is driven from the shaft by means of the intermeshing gears 167 and 168. This shaft 166 carries at its forward end a friction wheel 90 169. The friction wheel 165 and the wheel 169 are shiftable along the shafts 26 and 166 and are disposed opposite to each other. Mounted upon the shafts 26 and 166 are upwardly extending levers 170 and 171. 95 These levers may be mounted in any manner so long as they serve to move the wheels 165 and 169 along the faces of the disk 164 and toward and away from said disk. These levers are mounted and operate in a 100 manner similar to the levers 189 and 190 shown in Fig. 3. When the machine is not running, the lever 171 is moved inward, thus causing the friction wheels 165 and 169 to press very lightly, or not at all, upon 105 the friction disk 164. When, however, the upper end of the lever 171 is drawn outward, the wheels 165 and 169 will be forced against opposite faces of the friction disk 164 with a pressure depending upon the 110 force expended in drawing the lever 171 outward. It will be obvious that the rate of forward travel of the machine is entirely within the control of an operator standing at the front of the machine and manipulating the lever 171. When the friction wheels 165 and 169 are engaging with the friction disk 164, the winding shaft 158 will be rotated to wind up the flexible connection 157 in and thus move the machine 115 120 forward.

125 The steering of the machine is accomplished by means of a vertical worm shaft 181, mounted in suitable bearings at the forward end of the machine, and carrying the worm 182 which meshes with a gear wheel 183 upon a winding shaft 184. This winding shaft carries upon it the oppositely wound flexible connections 185 which extend each to one end of the front axle. 130

The speed whereby the excavating carrier is operating is controlled by means of the friction wheels 63 and 65 engaging with the friction disk 64, as previously described.

- 5 The wheel 63 is shiftably mounted upon the shaft 62. The wheel 64 is shiftably mounted upon a counter-shaft 186. This counter-shaft is driven from the shaft 62 by means of the gear wheels 187 and 188. The shaft 10 186 is supported at its rear end in a manner to admit of the forward end moving toward and from the friction disk 65. As illustrated in Fig. 3, the friction disks 63 and 64 are operated in the same manner and by the 15 same mechanism used for the friction wheels 165 and 169.

Bolted or otherwise attached to the under sides of the longitudinal beams forming the platform of the machine is a transversely 20 extending bolster 197 having downwardly depending front and rear flanges 198. Supported between these flanges 198 is one member of a fifth wheel, designated 199. The member 199 is connected to the bolster 197 25 by means of a pivot bolt 201. The other member 202 of the fifth wheel is connected to the axle 205 by means of clips 206. With this construction it is plain that the axle 205 may be oscillated in a vertical plane 30 without affecting the platform or frame of the machine.

The rear axle 217 is connected to the rear bolster 218 which extends across and beneath the longitudinal beams of the platform and 35 is attached thereto and is provided with the front and rear depending flanges 219. Mounted upon the axle 217 is a plate 220 having upwardly projecting lugs 212 which engage between the flanges 219 and are 40 pivoted thereto by means of a bolt 221. The plate 220 is held to the axle by means of U-bolts 222 and a plate 223. The platform is held in a horizontal position by means of 45 adjusting screws 224 and 225, which have screw threaded engagement with the ends of the bolster 218. The screw 224 engages a yoke 226 which loosely embraces the axle 217. Horizontal adjustment of the platform for leveling the same is obtained by rotating 50 the screws 224 in one direction or the other. The screw 225 may be used for securing the platform in the adjusted position by turning the screw to cause its lower end to engage the axle 217.

55 When the machine is at work and the trench is relatively deep, there is no necessity of using the leveling screw 224 as the weight of the depending sheathing members and the depending portion of the excavator will tend to keep the excavator and the frame-work and platform of the machine in proper position with the excavator extending vertically. Where the trench is relatively shallow, however, and most of the 60 weight of the excavator and sheathing mem-

bers is considerably above the platform of the machine, then the leveling screw 224 is particularly necessary.

When the machine is traveling over roads, the sheathing sections 119^a and 119^b may be 70 removed and carried upon the platform. At this time, the elevator frame and the sheathing section 119 are turned into a horizontal position. When the machine reaches the place where work is to be performed, a 75 trench is dug, sufficiently deep to permit the excavator frame and the sheathing section 119 to be turned into a vertical position. When the parts are properly arranged, the driving engine of the excavator is started 80 and the mechanism begins work. During this time the machine is moving forward by winding up the rope or cable 157 upon the shaft 158. As the machine moves forward, the excavator frame and the first section 119 85 attached thereto are gradually lowered by means of the winding shaft 52. This lowering continues until the full depth of the trench has been reached. After the excavator frame and the first section 119 have been 90 lowered to a proper degree, the second section 119^a of the sheathing is hung in place by means of the hinged joint previously referred to, and when the excavator frame and the sections 119 and 119^a 95 have been lowered a predetermined degree, the third section is added, and so on until as many sheathing sections are added as may be desirable. As the sheathing sections are added, the mixing drum is moved 100 back upon its tracks and, of course, each time that a new sheathing section is to be added, the chute 146 is shifted out of engagement with the sheathing section with which it was originally attached and into 105 engagement with the newly applied sheathing section. If, for any reason, the excavator is not tracking properly along the crown of the levee, it may be laterally adjusted relative to the frame of the machine 110 by means of the adjusting screw 80, and it will also be understood that as the sections are hingedly connected to each other they will track properly in the trench without binding, even though the line of the trench 115 may not be absolutely straight. The sections forming the sheathing members for the trench may be readily handled, lifted, lowered, &c., by means of the winch or windlass formed by the winding shaft 152. The 120 sections and excavator frame may be readily turned from a vertical to a horizontal position by means of this winch, the cable from which may be connected to the lower portion of the excavator frame, when it is desired to rotate it into a horizontal position, or lower it from a horizontal to a vertical position. The winding shafts 152 and 52 may also be used in connection with each other for the purpose of removing or apply- 125 130

ing the endless carrier of the excavator to the supporting wheels thereof. It is a very difficult matter to apply an endless carrier of this type to the sprocket wheels and stretch the carrier as it should be stretched, but by crossing the cables extending over the winding shafts 152 and 52 and passing them over the pulleys detachably mounted on the forward and rear standards and attaching them to opposite portions of the excavator carrier, when the same is in a horizontal position, these portions may be drawn together as tightly as necessary and the links of the carrier thus brought into position where they may be connected to each other.

In order to resist a pressure of the earth against the lower end of the excavator frame, and thus hold the excavator connecting links to their work, I may provide a spring 226 attached at one end between the beams 9 and at its other end attached to the upper end of the standard 34 at 227. It will thus be understood that the spring acts to draw the upper end of the standard rearward and thereby to draw the lower end of the excavator frame forward or against the work and resist pressure of the ground.

It will be seen that with a machine of the character described, it is possible to readily cut a core-trench longitudinally along the levee and fill this trench immediately with concrete, and it will also be plain that this concrete core or dike within a levee will tend to prevent the washing away of the levee and the destructive action of crawfish upon the levee. The advantages of a levee constructed with a core of stone are too obvious to need extensive statement.

While I have illustrated what I believe to be the best form of my invention, and have illustrated details of construction which are peculiarly adapted to the circumstances of the case, I do not wish to be limited to these details, as it is obvious that the machine may be modified in many ways without departing from the spirit of the invention.

What I claim is:

1. In a machine of the character described, a wheeled supporting frame, a standard pivotally mounted upon the frame for movement in a vertical plane, means for laterally shifting the standard relative to the frame, and trench excavating mechanism adjustable lengthwise of the standard and adjustable rotatably with the standard.

2. In a machine of the character described, a laterally and vertically movable trench excavating mechanism, a trench sheathing section support movable with said excavating mechanism, and a plurality of trench sheathing sections detachably connected to each other and to said support and extending rearward therefrom.

3. In a mechanism of the character de-

scribed, a vertically disposed laterally adjustable trench excavating mechanism, and a plurality of trench sheathing sections each including parallel spaced plates, the sections being detachably and hingedly connected to each other, the foremost section being flexibly connected to the excavating mechanism.

4. In a machine of the character described, a wheeled supporting frame, a vertically and laterally bodily disposed trench excavating mechanism mounted thereon, a trench sheathing section supported behind the excavating mechanism and having pivotal connection therewith and including spaced sheathing plates, a concrete mixer mounted on the frame, and means for conducting concrete from the mixer into the space between said plates.

5. In a machine of the character described, a wheeled supporting frame, trench excavating mechanism mounted on the frame, a trench sheathing section supported behind the excavating mechanism and including spaced plates, a concrete mixer slidingly mounted upon the frame, and a chute adjustably and detachably mounted upon the said section and adapted to convey mixture from the mixer to the space between the plates.

6. In a machine of the character described, a wheeled supporting frame, a vertically disposed trench excavating mechanism mounted upon said frame and depending below the same, means for vertically adjusting the excavating mechanism, a plurality of trench sheathing sections, each section including spaced plates, the lower ends of the plates being upwardly and rearwardly inclined, and said sections being detachably engaged with each other, a concrete mixer mounted upon the supporting frame for movement longitudinally thereon, and a chute conducting mixture from the mixer into the space between the plates of the rearmost shifting section.

7. In a machine of the character described, a wheeled supporting frame, a vertically disposed laterally adjustable trench excavating mechanism mounted upon said frame, means for laterally adjusting the trench excavating mechanism relative to the frame, a plurality of trench sheathing sections disposed successively rearward of the trench excavating mechanism, the sections being detachably and hingedly connected to each other, the sections being successively shorter toward the rear end of the machine and each having downwardly and forwardly inclined lower ends, and a chute detachably and adjustably connected with the rearmost section.

8. In a machine of the character described, a wheeled frame, a vertically disposed trench excavating mechanism mounted upon said wheeled frame for vertical adjustment,

means for laterally adjusting said excavating mechanism relative to the frame, a plurality of sheathing sections disposed one behind another rearward of the frame and detachably and hingedly engaged with each other, each section including spaced plates, and each section being successively shorter from front to rear, the lower end of the sections being inclined downward and forward and being open at their bottoms, a concrete mixer longitudinally adjustable along the frame and having a discharge spout, and a chute detachably and adjustably mounted upon the rearmost section and having a lateral elongated mouth receiving the concrete from the said spout.

9. A machine of the character described including a wheeled supporting frame, vertically disposed trench excavating mechanism mounted upon said frame, a trench sheathing section supported rearward of the excavating mechanism and including spaced plates, said section being closed along its vertical front side, the front wall of the section extending parallel to the excavating mechanism, the bottom of the section being closed adjacent the front wall and said bottom inclining downwardly and rearwardly whereby to form a shoe bearing against the bottom of the trench, and means mounted upon the wheeled frame for discharging concrete mixture between the side plates of said sheathing section.

10. In a machine of the character described, a wheeled supporting frame, a trench excavating mechanism comprising upper and lower sprocket wheels, an endless excavating element passing over the sprocket wheels, side plates supporting the sprocket wheels and the endless element, means connected to the upper ends of the side plates for vertically adjusting the side plates, sprocket wheels and the endless element, means for driving the sprocket wheels, and means slidably engaging the lower ends of the side plates and holding them in parallel relation to the endless excavating element.

11. In a mechanism of the character described, a wheeled supporting frame, a vertically disposed standard pivotally mounted on the frame for movement in a vertical plane longitudinally of the machine, excavating mechanism including upper and lower sprocket wheels, vertically disposed spaced plates supporting said sprocket wheels, and an endless excavating element passing over the sprocket wheels, a slide to which the upper ends of the side plate are connected, said slide engaging the vertical standard, means for raising and lowering the slide along the standard to thereby vertically adjust the excavating mechanism, and means for locking the slide in its adjusted position upon said standard.

12. In a mechanism of the character de-

scribed, a wheeled supporting frame, a vertical standard pivoted upon the frame for movement in a vertical plane longitudinally of the machine, a slide shiftably engaging said standard, vertically extending, laterally spaced plates attached at their upper ends to said slide, sprocket wheels disposed at the upper and lower ends of the plates and between the same, an endless excavating element carried by said sprocket wheels, means for raising and lowering the slide, means for locking the slide to the standard, and means connecting the lower end of the standard with the said side plates and vertically movable with relation thereto.

13. In a mechanism of the character described, a wheeled supporting frame, a vertically disposed standard, an interiorly screw threaded trunnion upon which the standard is mounted for rotary movement in a vertical plane, a feed screw engaging said trunnion whereby it may be shifted laterally, and trench excavating mechanism slidably mounted upon said standard and rotatable from a vertical to a horizontal plane with the standard.

14. In a machine of the character described, a wheeled supporting frame, a vertically disposed standard, a trunnion mounted on the frame and pivotally supporting the standard at its lower end, said trunnion having a screw threaded bore in one end and a bore in the other end, an adjusting screw engaging the screw threaded end of the trunnion, a shaft supported at its inner end in the other bore of the trunnion, and carrying a bevel gear wheel, an excavating mechanism slidably mounted upon the standard and extending vertically downward and including opposed sprocket wheels and an endless excavating member, a vertical shaft supported parallel to said excavating mechanism, a bevel gear wheel splined on said shaft and engaging a bevel gear wheel mounted on a sprocket wheel shaft, a bevel gear wheel carried on the lower end of the vertical shaft and engaging the first named bevel gear wheel, and means for transmitting power to the shaft of said last named bevel gear wheel.

15. In a machine of the character described, a wheeled supporting frame, forward and rear vertical supporting standards, longitudinally extending beams operatively connected to the upper ends of the standards, a supporting standard disposed at the forward end of the machine and pivotally mounted at its lower end for movement in a vertical plane, excavating mechanism slidably mounted upon said supporting standard but rotatable therewith from a vertical to a horizontal position, a winding drum mounted on the longitudinally extending beams, and operative connections between the winding drum and said excavating mech-

anism whereby the latter may be shifted vertically.

16. In mechanism of the character described, a wheeled supporting frame, a standard pivotally mounted at its lower end upon said frame for movement in a vertical plane, a slide mounted on the standard, excavating mechanism carried by and depending from said slide, a feed screw operatively engaging the lower end of the standard to shift it and the excavating mechanism laterally, a feed screw engaging the upper end of the standard, sprocket wheels on said screws, and an endless connection passing over the sprocket wheels.

17. In a machine of the character described, a wheeled supporting frame, a standard pivotally mounted at its lower end upon said frame for movement in a vertical plane, a slide carried by the standard and vertically shiftable therealong, excavating mechanism depending from the slide and movable therewith, means for vertically moving the slide, a feed screw operatively engaging the lower end of the standard, a feed screw extending transversely to the upper end of the standard, ears having screw threaded engagement with the last named feed screw, and embracing the standard, and means for coincidentally operating both of the feed screws.

18. In a machine of the character described, a wheeled frame, a standard projecting upward at the forward end of the wheeled frame, a slide mounted on the standard, hangers depending from the slide, bearings mounted on said hangers, an upper sprocket wheel shaft mounted in said bearings, a sprocket wheel carried thereby, spaced side plates attached at their upper ends to said slide and disposed on each side of the sprocket wheel, a lower sprocket wheel mounted in the lower ends of the side plates, an endless excavating element mounted on said sprocket wheels, means for raising and lowering the slide relative to the standard, a supporting member projecting rearward from the slide, a sheathing section supported by said member and having its forward edge spaced from the rear edges of the side plates and extending parallel thereto, and means for driving said sprocket wheels.

19. In a machine of the character described, a wheeled supporting frame, trench excavating mechanism carried thereby, a sheathing member supported rearward of the excavating member, a chute coacting with the sheathing member and linked thereto for vertical movement, and runners attached to the sheath and adapted to contact with the

ground whereby to raise and lower the chute.

20. In a machine of the character described, a wheeled supporting frame, vertically disposed standards at opposite ends of the frame, longitudinally extending beams connecting the upper ends of the standards, vertically movable trench excavating mechanism mounted upon said frame, detachable trench sheathing sections comprising spaced plates and disposed rearward of the excavating mechanism, winding mechanism mounted upon the longitudinal beams above the excavating mechanism and adapted to raise or lower the latter, and winding mechanism mounted at the rear end of the machine upon said supporting beams and including a cable adapted to be connected to the said sheathing sections.

21. In a machine of the character described, a wheeled supporting frame, trench excavating mechanism depending from said frame, trench sheathing sections operatively supported rearward of the excavating mechanism and flexibly connected thereto, means for steering the frame, and means for laterally shifting the excavating mechanism relative to the frame.

22. In a machine of the character described, a wheeled supporting frame, laterally adjustable trench excavating mechanism supported by and depending from said frame, trench sheathing sections hingedly connected to each other and supported rearward of the excavating mechanism and flexibly connected thereto, means for drawing the frame forward, and means for steering the frame.

23. In a machine of the character described, a supporting frame, vertically disposed trench excavating mechanism mounted on and depending from the supporting frame, and a plurality of trench sheathing members disposed successively behind the excavating mechanism and comprising spaced side plates, both of said members having coacting hinge elements near their lower ends, one of said elements comprising a pintle and the other a socket, both of said members having coacting hinge elements at their upper ends comprising perforated ears, and a removable pintle detachably engaging said ears.

In testimony whereof I affix my signature in presence of two witnesses.

JOHN J. CRALL. [L.S.]
